UNITED STATES PATENT OFFICE.

DAVID KOENIG, OF NEW YORK, N. Y., ASSIGNOR TO WESTERN ELECTRIC COMPANY, OF NEW YORK, N. Y., A CORPORATION OF ILLINOIS.

TELEPHONE-TRANSMITTER.

1,138,959.

Specification of Letters Patent.

Patented May 11, 1915.

Application filed March 21, 1911. Serial No. 615,825.

To all whom it may concern:

Be it known that I, DAVID KOENIG, subject of the King of Hungary, residing at New York, in the county of New York and State of New York, have invented a certain new and useful Improvement in Telephone-Transmitters, of which the following is in full, clear, concise, and exact description.

My invention relates to telephone transmitters and its object is to provide a simplified and improved construction for conducting away the heat generated in such instruments whereby the strength of current may be increased without burning the carbon granules and therefore the instrument made more sensitive and powerful for the transmission of speech.

According to the invention, the carbon chamber is surrounded by a large block of good conducting material having a flaring opening forming the side walls of the chamber. The smaller end of the opening is opposite and closely adjacent to the front electrode, while the larger opening is opposite but not so close to the back electrode. By reason of this construction, the front electrode may be placed very close to the inner edge of the heat absorbing block and the carbon granules may lie in direct contact with the naked walls of the block without danger of burning the granules by excessive current at the edges of the electrodes.

The invention will be more fully understood by reference to the accompanying drawing in which—Figure 1 is a rear elevation with the casing removed of a telephone transmitter embodying the invention and Fig. 2 is a sectional view of the same.

In the drawing, the elements of the transmitter are mounted on the rear side of a face plate 1, to which is attached a mouth piece 2, and inclosed within a casing 3. The transmitter elements comprise the usual diaphragm 4, front and back electrodes, 5 and 6, bridge piece 7, supporting the back electrode, terminal blocks 8, 8 and mica diaphragm 9. The back electrode is seated in a block 10, of good conducting material such as copper or brass to absorb the heat generated in the back electrode. Secured to the block 10 by screws 14, 14 but insulated therefrom by means of an insulating washer 15 and bushings 16, 16 is a block of like heat conducting material comprising the parts

11, 12, these parts being externally and internally threaded at 13 to provide for clamping the edge of the mica diaphragm 9. 55

The part 11, it will be noted, has a flaring opening and thus forms with the front and back electrodes a chamber which has naked and flaring side walls. The part 11, 60 although lying close to the front electrode permitting rapid heat conduction therefrom, is more widely separated from the back electrode, the heat generated in which is more 65 easily taken care of by the block 10 in which it is seated. Short paths for the current from the edge of one electrode to the edge of the other by way of the heat conducting block part 11 are thus avoided while permitting the maximum heat conduction from 70 the several parts of the transmitter button.

I claim:

1. In a telephone transmitter, an electrode chamber comprising a block of heat-conducting material, an electrode embedded therein, a second block of heat-conducting material having a flared central opening and insulated from said first mentioned block, and an electrode flexibly supported in said 80 opening opposite said first mentioned electrode. 75

2. In a telephone transmitter, an electrode chamber comprising a block of heat-conducting material having an insulated face, 85 an electrode embedded in said block, a second block of heat-conducting material contiguous to said insulated face and having a flared central opening, the larger end of which is of greater diameter than said electrode and adjacent said insulated face, and a second electrode flexibly supported within 90 said opening opposite said first mentioned electrode. 90

3. In a telephone transmitter, a pair of 95 electrodes forming opposite walls of a granular chamber and a block of heat conducting material having a flaring opening forming the side walls of said chamber, the smaller end of said flaring opening being 100 opposite and closely adjacent one of said electrodes and the opposite end of said flaring opening being opposite the other of said electrodes but separated therefrom.

4. In a telephone transmitter, a movable 105 and a stationary electrode, a block of heat conducting material upon which said stationary electrode is supported, a second

block of heat conducting material having a naked flaring wall forming the side wall of a granular chamber, the larger end of said wall being opposite said stationary electrode and of larger diameter than said electrode and the smaller end thereof being opposite said movable electrode.

In witness whereof, I hereunto subscribe my name this 18th day of March, A. D. 1911.

DAVID KOENIG.
